UNITED STATES PATENT OFFICE.

ANDREW SYROCKI, OF DETROIT, MICHIGAN.

DESIGN FOR A COMBINED BIRD-CAGE AND AQUARIUM.

53,157.

Specification for Design.

Patented Apr. 1, 1919.

Application filed February 10, 1919. Serial No. 276,243. Term of patent 14 years.

To all whom it may concern:

Be it known that I, ANDREW SYROCKI, a citizen of the United States, residing at Detroit, in the county of Wayne and State of Michigan, have invented a new, original, and ornamental Design for a Combined Bird-Cage and Aquarium, of which the following is a specification, reference being had to the accompanying drawing, forming part thereof.

Figure 1 is a perspective view of the bird cage and aquarium as viewed from one direction.

Fig. 2 is a perspective view of the same viewed from the opposite direction.

I claim:

The ornamental design for a combined bird cage and aquarium, as shown.

In testimony whereof I sign this specification in the presence of two witnesses.

ANDREW SYROCKI.

Witnesses:

S. E. THOMAS,
EDWIN R. MONNIG.
